UNITED STATES PATENT OFFICE.

OSCAR E. BRANDT, OF CHICAGO, ILLINOIS, ASSIGNOR TO THE W. W. KIMBALL COMPANY, OF SAME PLACE.

DESIGN FOR THE TOP OF AN ORGAN-CASE.

SPECIFICATION forming part of Design No. 21,881, dated October 4, 1892.

Application filed April 11, 1892. Serial No. 428,718. Term of patent 3½ years.

To all whom it may concern.

Be it known that I, OSCAR E. BRANDT, a citizen of the United States, residing at Chicago, in the county of Cook and State of Illinois, 5 have invented a new and original Design for the Top of an Organ-Case, of which the following is a specification.

This invention is a design for the tops of organ-cases, and is shown in perspective in 10 the accompanying drawing.

The leading feature of the design is found in the three mirrored sections, each surmounted by an arch and radiating spindles.

In the drawing, A represents the center section, and B B the side sections, of the top. 15 Each section is composed in the main of a mirror C and an arch D, surmounting the mir-

ror and provided with radiating spindles d. These arches and their spindles much resemble the half of a spoked wheel in appearance, 20 the spindles radiating from a center or hub E. The three sections are relatively arranged as shown upon the top board G of the organ—that is to say, the center section stands parallel with the front of the organ, while the 25 side sections are placed diagonally.

I claim—

The design for the top of an organ-case, substantially as herein shown.

OSCAR E. BRANDT.
